RAILWAY SIGNALING

George R. Pflasterer, Swissvale, Pa., assignor to
The Union Switch & Signal Company, Swiss-
vale, Pa., a corporation of Pennsylvania

Application August 27, 1936, Serial No. 98,211

3 Claims. (Cl. 246—50)

My invention relates to railway signaling, and particularly to signaling involving wayside signals located along a trackway for governing the passage of trains.

A feature of my invention is the provision of novel and improved apparatus for establishing a distinctive control for each of three sections in the rear of an occupied section. Each distinctive control is effective to cause a corresponding aspect of the associated wayside signal whereby there is produced a three-block, four-indication, system of signaling.

The system provided by this invention is an improvement over that shown and claimed in an application of Howard A. Thompson, for Railway traffic controlling apparatus, filed October 4, 1933, Serial No. 692,155; in an application of Henry S. Young, for Railway signaling, filed February 27, 1936, Serial No. 66,002; in United States Patent No. 2,123,922, issued July 19, 1938, to Leslie R. Allison, for Railway signaling; and in United States Patent No. 2,123,962, issued July 19, 1938, to me, for Railway signaling.

I will describe three forms of apparatus embodying my invention, and will then point out the novel features thereof in claims.

Figs. 1A and 1B of the accompanying drawings are diagrammatic views, which when placed end to end in the order named, illustrate one form of apparatus embodying my invention. Figs. 2 and 3 are diagrammatic views illustrating modifications of a portion of the apparatus shown in Fig. 1A and each also embodying my invention.

Similar reference characters refer to similar parts in each of the several views.

Referring first to Figs. 1A and 1B, the reference characters 7 and 8 designate the rails of a stretch of track over which traffic normally moves in the direction indicated by the arrows. The rails 7 and 8 are divided by insulated joints 9 into track sections W—X, X—Y, and Y—Z. Each track section is divided into at least two sub-sections 1T, 2T, 3T, 4T, etc. Each sub-section is provided with a track battery 10 connected across the rails at one end of the sub-section and with a track relay, designated by the reference character TR with a prefix the same as the numerical prefix of the associated sub-section, connected across the rails at the other end of the sub-section.

To govern the passage of trains through the stretch of railway, a wayside signal designated by a suitable distinguishing reference character, is provided for each track section. Each of these signals includes an upper indication unit U and

a lower indication unit L. These units may take any one of several forms of signal mechanism such as semaphore, color light, searchlight, or position light. As here shown, each upper unit U is a color light signal including a "stop" lamp R capable of displaying a red light, a "caution" lamp Y capable of displaying a yellow light, and a "proceed" lamp G capable of displaying a green light; and each lower unit L is a "proceed" lamp G capable of displaying a green light.

For controlling the signals, each section is provided with a polarized direct current neutral relay and with an alternating current undervoltage relay designated by the reference characters HD and LV, respectively, each with a prefix the same as the reference character of the associated signal.

For controlling the relays HD and LV, each section is provided with a pair of line conductors each extending to the signal in advance and each including a front contact of each of the associated track relays. The relays HD are directly connected to the associated pair of line conductors and the relays LV are connected to the associated line conductors by a transformer designated by 25 the reference character M with a prefix the same as the reference character of the associated signal. As will be explained more in detail hereinafter, the line conductors of each section are at times supplied with alternating current as well as with 30 direct current. The impedance of the polarized relays HD is of such value as will prevent the flow of alternating current in these relays and the resistance of the primary windings 24 of the transformers M is of such value as will substantially 35 prevent the flow of direct current in these transformers. In addition, condensers Q are interposed in the circuits leading from the line conductors to the primary windings of the transformers M to prevent flow of direct current from 40 the line conductors to the transformers.

For controlling the signal lamps, each section is provided with an approach lighting relay designated by the reference character ER with a prefix the same as the reference character of the 45 associated signal. The relays ER are connected in series with the line conductors for the section next in rear and is therefore energized at all times except when that line circuit is open. That is, the approach lighting relays ER become released only when the section immediately to the rear of the signal with which such relay is associated becomes occupied by a train. Since the impedance of the relays ER is of such value as 50 will substantially block the passage of alternating 55

current, a resistor 16 for bypassing the alternating current is connected around each relay ER.

The character and direction of the energy supplied to the line conductors for the section next in rear is governed by the relay HD associated with the section in advance. That is, the line conductors for such section in the rear are supplied with direct current of normal or reverse polarity according as the relay HD associated with the section in advance is energized or deenergized, respectively, and when the relay HD is energized in the normal direction, the line conductors to the rear are supplied with alternating current simultaneously with direct current in the normal direction.

Each section is provided with a source of direct current, here shown as a battery 11, the terminals of which are designated by the reference characters B and C.

For supplying alternating current to the associated line circuit, each section is provided with a transformer, designated by the reference character N with a prefix the same as the reference character of the associated signal, having a primary winding 22 and a secondary winding 23. Each secondary winding 23 is connected in series with the line conductors for the section in the rear.

For supplying alternating current to the primary winding 22 of the transformers N, each section is provided with a device designated by the reference character A with a prefix the same as the reference character of the associated signal.

As here shown, each device A is an alternator of the vibrating reed type. Referring to alternator 13A, for example, an elastic member 17 is caused to vibrate between terminals 18 and 19 by a control winding 20. In the deenergized condition of alternator A, member 17 does not connect with either terminal 18 or 19 but does connect with a terminal 21. When energy is supplied to the alternator, winding 20 will attract member 17 causing it to connect with terminal 19 and to move away from terminal 21 thereby causing winding 20 to become deenergized. Upon the deenergization of winding 20, the resilience of member 17 will cause it to move away from terminal 19 and to connect with terminal 18 as well as with terminal 21. The circuit for winding 20 being then again completed through terminal 21, winding 20 will again attract member 17 causing the cycle of operation just described to be completed. Winding 20, therefore, will be repeatedly energized and deenergized as long as energy is supplied to its control circuit. When member 17 is in engagement with contact 18, the left-hand portion of primary winding 22 of transformer 13N will be energized in one direction whereas, when member 17 is in engagement with contact 19, the right-hand portion of primary winding 22 will be energized in the reverse direction. Alternating current, therefore, will be induced in secondary winding 23 of transformer 13N as long as alternator 13A is operating.

The polarized direct current relays HD and the alternating current low voltage relays LV control the signals in the following manner: When relay HD is deenergized (see signal 15), a circuit is established for the stop lamp R of the upper unit U so that when relay 15ER becomes released, the signal will display a red light to indicate "stop". This circuit may be traced from terminal B through back contact 26 of relay 15ER, back point of contact 27 of relay 15HD, and lamp R to

terminal C. When relay HD is energized in the reverse direction (see signal 14), a circuit is established for the caution lamp Y of the upper unit U so that when relay 14ER becomes released, the signal will display a yellow light to indicate "approach next signal prepared to stop". The circuit for lamp Y may be traced from terminal B through back contact 28 of relay 14ER, front point of contact 29 of relay 14 HD, the reverse polar contact 30-31 of relay 14HD, and lamp Y to terminal C. When relay HD is energized in the normal direction (see signal 13), a circuit for the proceed lamp G of the upper unit U is established so that, when relay 13ER becomes released, the signal will display a single green light to indicate "approach next signal at medium speed". The circuit for lamp G of the upper unit U may be traced from terminal B through back contact 32 of relay 13ER, front point of contact 33 of relay 13HD, normal polar contact 30-34 of relay 13HD, and lamp G to terminal C. When the line circuit is supplied with alternating current simultaneously with direct current in the normal direction (see signal 12), the releasing of relay 12ER will close the previously traced circuit for the lamp G of the upper unit U and relay 12LV will become energized by secondary winding 25 of transformer 12M to close a circuit for the lamp G of the lower unit L over front contact 35 of relay 12LV so that the signal will display a green light over a green light to indicate "proceed at normal speed".

As here shown, a train K is indicated diagrammatically in the section immediately to the right of location Z so that relay 15HD is deenergized to cause signal 15 to assume the condition for the display of the stop indication. Since relay 15HD is deenergized, relay 14HD is energized in the reverse direction over a path which passes from terminal B of battery 11 at signal 15 through resistor 16 and relay 15ER in multiple, back point of contact 49 of relay 15HD, secondary winding 23 of transformer 15N, front point of contact 41 of relay 6TR, front point of contact 42 of relay 5TR, relay 14HD, front contact 43 of relay 5TR, front contact 44 of relay 6TR, and back point of contact 45 of relay 15HD to terminal C of battery 11.

Since relay 14HD is energized, relay 13HD is energized in the normal direction over a path which passes from terminal B of battery 11 at signal 14 through resistor 16 and relay 14ER in multiple, front point of contact 46 of relay 14HD, front contact 47 of relay 4TR, front contact 48 of relay 3TR, relay 13HD, front contact 49 of relay 3TR, front contact 50 of relay 4TR, secondary winding 23 of transformer N, and front point of contact 51 of relay 13HD to terminal C of battery 11.

Since relay 13HD is energized in the normal direction, relay 12HD is energized in the normal direction over a path similar to that just traced for the relay 13HD and the operation of alternator 13A is initiated to supply alternating current to transformer 12N. The circuit for alternator 13A passes from terminal B of front contact 52 of relay 13HD, normal polar contact 53-54 of relay 13HD, and alternator 13A to terminal C. Since alternator 13A is operating, transformer 12M is energized with alternating current which passes over a path from one terminal of secondary winding 23 of transformer 13N through front point of contact 55 of relay 13HD, battery 11 at signal 13, resistor 16 and relay 13ER in multiple, front point of contact 56 of

relay 13HD, front contact 57 of relay 2TR, front contact 58 of relay 1TR, front contact 59 of relay 12HD, normal polar contact 60-61 of relay 12ER, primary winding 24 of transformer 12M, condenser 12Q, front contact 63 of relay 1TR, and front contact 64 of relay 2TR to the other terminal of secondary winding 23 of transformer 13N. A circuit therefore is established for primary winding 24 of transformer 12N so that, when relay 12ER becomes released to close its back contact 62, energy will be induced in secondary winding 25 of transformer 12N to cause relay 12LV to become energized.

It will be readily apparent that the proceed lamps G of the lower unit could be connected directly to secondary winding 25 of the associated transformer M, thereby eliminating the low voltage relays LV. The relays LV, however, are provided to insure against the possibility of the associated lamp G becoming partially energized by foreign current of a voltage lower than the normal lamp voltage which current may be induced in the line conductors from, for example, an adjacent transmission line.

The relays HD are provided with a retained neutral characteristic in order to avoid tumble-down of signal control circuits to the rear during pole changing periods. For example, when the train K passes out of the section immediately to the right of location Z so that the energization of the relay 14HD is changed from the reverse direction to the normal direction, front points of contacts 46 and 51 of relay 14HD remain closed so that the energization of the line conductors for the section X-Y is not disturbed.

Referring next to Fig. 2, I have shown herein one signal and associated apparatus which, when included in a system with wires 70 and 71 at the right connected to wires 72 and 73, respectively, at the left, will provide a three-block, four-indication, system of signaling similar to that described for the system shown in Figs. 1A and 1B. The principal difference between the system illustrated in Fig. 2 and the system illustrated in Figs. 1A and 1B is in the indications displayed by the signal. That is, in Fig. 2, the normal proceed indication is a single green light and the approach next signal at medium speed indication is a yellow light over a yellow light, whereas in Figs. 1A and 1B the normal proceed indication is a green light over a green light and the approach next signal at medium speed indication is a single green light.

The relay HD controls the lamps of the upper unit U in a manner similar to that described for the system shown in Figs. 1A and 1B. That is, the stop lamp R becomes energized when the relay HD is deenergized and the caution lamp Y or proceed lamp G becomes energized when the relay HD is energized in the reverse direction or the normal direction, respectively. The caution lamp Y of the lower unit L receives energy direct from the line conductors of the forward section through the usual transformer M, while a condenser Q is interposed in the circuit leading to the primary winding 24 of the transformer M to prevent flow of direct current from the line conductors to the transformer.

Connected in series with the lamp Y of the lower unit L is an alternating current relay designated by the reference character LY and connected in series with the caution lamp Y of the upper unit U is a direct current relay designated by the reference character UY.

The relays HD, LY, and UY control the energy supplied to the line conductors for the rear section in the following manner: When the relay HD is deenergized, the line conductors for the rear section will be supplied with direct current in the reverse direction over the back points of contacts 74 and 75 of relay HD. When relay HD is energized in the reverse direction and the relay LY is deenergized, the line conductors for the rear section will be supplied with direct current energy in the reverse direction and the operation of the alternator A will be initiated. The path for the direct current energy includes front points of contacts 74 and 75 of relay HD, reverse polar contacts 76-77 and 78-79 of relay HD, and back points of contacts 80 and 81 of relay LV. The circuit for alternator A passes from terminal B over back point of contact 82 of relay LV, front contact 83 of relay HD, reverse polar contact 84-85 of relay HD, and alternator A to terminal C. The path for supplying alternating current to the rear line circuit includes secondary winding 23 of transformer N and front points of contacts 74 and 75 of relay HD. When relay HD is energized in the reverse direction and both relays LY and UY are energized, the line conductors for the rear section will be supplied with direct current in the normal direction over a path which includes front points of contacts 74 and 75 of relay HD, reverse polar contacts 76-77 and 78-79 of relay HD, front points of contacts 80 and 81 of relay LY, and front points of contacts 86 and 87 of relay UY. When relay HD is energized in the normal direction, as shown in the drawings, the line conductors for the rear section are energized by direct current in the normal direction over front points of contacts 74 and 75 of relay HD and normal polar contacts 76-88 and 78-89 of relay HD.

It will be noted that, when the relay HD is energized in the reverse direction, both relays LY and UY must be energized before the rear line circuit can be supplied with energy in the normal direction to cause the signal (not shown) controlled by that line circuit to display the normal proceed indication. Since the relays LY and UY are connected in series with the caution lamps Y of the lower unit and upper unit, respectively, this feature insures that the filaments of both lamps must be intact before a proceed indication can be displayed at the signal next in rear.

Furthermore, if either lamp Y fails to become illuminated when traffic conditions are such that both lamps should be lighted, that is, if the signal is displaying one yellow light to indicate "approach next signal prepared to stop" when it should be displaying two yellow lights to indicate "approach next signal at medium speed", then the rear line circuit will be conditioned so that the signal (not shown) controlled by that line circuit will be displaying two yellow lights to indicate "approach next signal at medium speed". For example, if lamp Y of the upper unit U should become burned out so that relay UY becomes released when both lamps Y should be illuminated, the rear line circuit will be supplied with direct current in the reverse direction and the operation of alternator A will be initiated so that alternating current also will be supplied to the rear line circuit. The circuit for alternator A may be traced from terminal B through back contact 90 of relay UY, front point of contact 82 of relay LY, front contact 83 of

relay HD, reverse polar contact 84—85 of relay HD, and alternator A to terminal C. The path for supplying direct current in the reverse direction to the rear line circuit includes back 5 points of contacts 86 and 87 of relay UY, front points of contacts 80 and 81 of relay LY, reverse polar contacts 76—77 and 78—79 of relay HD, and front points of contacts 74 and 75 of relay HD. Alternating current will be supplied 10 to the rear line circuit over the usual path which includes secondary winding 23 of transformer N and front points of contacts 74 and 75 of relay HD. The rear line circuit, therefore, will be energized with direct current in the reverse direction 15 as well as with alternating current so that a signal which may be controlled by such line circuit will be in condition to display a yellow light over a yellow light to indicate "approach next signal at medium speed".

20 Referring now to Fig. 3, I have shown herein one signal and associated apparatus which when connected in a system will provide three-block, four-indication, signaling similar to that described for the system shown in Figs. 1A and 1B. The principal difference between the system illustrated in Fig. 3 and the system illustrated in 25 Figs. 1A and 1B is that in Fig. 3 the signal is controlled directly over the track rails, thereby dispensing with the necessity for the use of line 30 conductors. A polarized track relay TR connected to the rails of the forward section controls the lamp circuits for the upper unit U and the energy supplied to the rails of the rear section in the usual manner. That is, the stop 35 lamp R will be energized when the relay TR becomes deenergized to close back point of contact 91 of relay TR and the caution and proceed lamps will be energized, when front point of contact 91 is closed, according as the relay TR is 40 energized in the reverse and normal directions to close polar contacts 92—93 and 92—94, respectively. The rails of the rear section are supplied with direct current energy from a track battery TB in the normal and reverse directions 45 according as the relay TR is energized or deenergized to close contacts 95 and 96 at their front or back points, respectively. When the relay TR is energized in the normal direction, as shown, the operation of alternator A is initiated so that 50 alternating current will be supplied to the rails of the rear section simultaneously with direct current. The circuit for alternator A includes front contact 97 and normal polar contact 98—99. The transformer M controls the proceed lamp 55 G of the lower unit L in the usual manner. That is, secondary winding 25 is connected direct to the lamp G and primary winding 24 is connected over a front contact of the relay TR and condenser Q to the rails of the forward section. 60 The condenser Q is provided to prevent the flow of direct current in the primary winding 24. The relay TR is provided with a retained neutral 65 characteristic for the usual purpose, that is, to avoid tumble-down from the signal control circuits to the rear during pole changing periods. This feature also insures against a momentary energization of the stop lamp R during such periods of change in polarity.

In view of the similarity of the operation of the apparatus shown in Fig. 3 to the operation of the apparatus shown in Figs. 1A and 1B, it is believed that further detailed description is unnecessary.

5 Although I have herein shown and described only three forms of apparatus embodying my invention, it is understood that various changes and modifications may be made therein within the scope of the appended claims without departing from the spirit and scope of my invention.

10 Having thus described my invention, what I claim is:

1. In combination, a forward and a rear section 15 of railway track, a signal for the forward section including a first lamp and a second lamp, means effective when the forward section is unoccupied to light only said first lamp or to light both said lamps in accordance with traffic conditions in advance of the forward section, a first 20 relay connected in series with said first lamp, a second relay connected in series with said second lamp, a pair of conductors for the rear section governed by traffic conditions in that 25 section, and means including contacts of said first and said second relays for controlling the character and direction of the energy supplied to said pair of conductors.

2. In combination, a forward and a rear section 30 of railway track, a signal for the forward section including a first lamp and a second lamp, means effective when the forward section is unoccupied to light only said first lamp or to light both said lamps in accordance with traffic conditions in advance of the forward section, a first 35 relay connected in series with said first lamp, a second relay connected in series with said second lamp, a pair of conductors for the rear section governed by traffic conditions in that section, means effective when both said first and 40 said second relays are energized to supply said pair of conductors with only current of one character, and means effective when either of said relays is deenergized to supply said pair of conductors with current of another character simultaneously with current of said one character.

3. In combination, a forward and a rear section 45 of railway track, a signal for the forward section including a first lamp and a second lamp, means effective when the forward section is unoccupied to light only said first lamp or to light both said lamps in accordance with traffic conditions in advance of the forward section, a first 50 relay connected in series with said first lamp, a second relay connected in series with said second lamp, a pair of conductors for the rear section governed by traffic conditions in that section, means effective when both said first and 55 said second relays are energized to supply said pair of conductors with only direct current in one direction, and means effective when either of said relays is deenergized to supply said pair of conductors with alternating current simultaneously with direct current in the other direction. 60 65

GEORGE R. PFLASTERER.
